US0D1107684S

(12) **United States Design Patent** (10) Patent No.: **US D1,107,684 S**
(45) Date of Patent: ** Dec. 30, 2025

(54) **HEADPHONE**

(71) Applicant: **SHENZHEN SHOKZ CO., LTD.**,
Guangdong (CN)

(72) Inventors: **Lei Zhong**, Shenzhen (CN); **Sunjie Huang**, Shenzhen (CN); **Zeteng Yan**, Shenzhen (CN); **Haochen Liu**, Shenzhen (CN); **Shuailin Xie**, Shenzhen (CN)

(73) Assignee: **SHENZHEN SHOKZ CO., LTD.**,
Shenzhen (CN)

(**) Term: **15 Years**

(21) Appl. No.: **30/009,451**

(22) Filed: **Jun. 20, 2025**

Related U.S. Application Data

(62) Division of application No. 35/522,477, filed on Sep. 22, 2023 (U.S. filing date under 35 U.S.C. 384), and having an international filing date of Sep. 22, 2023.

(30) **Foreign Application Priority Data**

Apr. 23, 2023 (CN) 202330228921.3
Aug. 11, 2023 (CN) 202330514251.1

(51) **LOC (15) Cl.** **14-01**

(52) **U.S. Cl.**

USPC **D14/205**

(58) **Field of Classification Search**

USPC D14/205, 188, 192; D24/174; 128/864-866; 381/380-381; 362/105

(57) **CLAIM**

The ornamental design for a headphone as shown and described.

DESCRIPTION

FIG. 1 is a top perspective view of a headphone according to our new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

1 Claim, 8 Drawing Sheets
